CLAIM

The ornamental design for a water filter for home use,
as shown and described.

DESCRIPTION

FIG. 1 is a front elevational view of a water filter for
home use showing our new design;

FIG. 2 is a right side elevational view thereof, the left
side being a mirror image;

FIG. 3 is a rear elevational view thereof;

FIG. 4 is a top plan view thereof;

FIG. 5 is a bottom plan view thereof.

FIG. 1

FIG. 3

FIG. 2

FIG. 2

FIG. 5
